EDWIN R. CROOKER AND HARRY C. NEWMAN, OF LOS ANGELES, CALIFORNIA; SAID
NEWMAN ASSIGNOR TO SAID CROOKER.

ELECTRIC HEATER.

Application filed February 6, 1925. Serial No. 7,235.

Our present invention is an electric heater which is suitable for various uses, and which is not liable easily to get out of order, although it is adapted to be manufactured and 5 sold at comparatively small cost.

It is an object of this invention to provide an electric heater which, although it may be rigid, is sufficiently flat and thin to be suitable for, for example, hospital uses, such 10 as the warming of a bed or of parts of the human body; and a preferred embodiment of this invention may comprise a sheet metal casing adapted to receive and to protect all essential parts thereof, retaining the same 15 in their intended relationships, this container being suitable, upon the removal of an optional cloth cover therefrom, for insertion, in the customary manner of an immersion heater, in liquids, or the like.

20 It is a further object of this invention to provide an electric resistance heater of the constant potential type in which especially simple and effective means are employed for supporting an insulating and heating element 25 and electrical contacts; and a preferred embodiment of our invention may comprise simple and effective means enabling a low-potential lamp to be advantageously used in indicating whether or not suitable current 30 is actually being supplied to the coils of a comparatively high-potential heater.

It is a further object of our invention to provide a resistance heater of the general type referred to, with internal but readily 35 adjustable automatic means for the maintenance of a substantially constant temperature.

It is a further object of this invention to 40 provide an electric heater comprising comparatively simple and rugged means for attaching a flexible cord thereto; and a preferred embodiment of our invention may comprise contact elements respectively secured to inner and outer insulating plates 45 and accessible for adjustment or repair, although the heating element of our heater is preferably permanently secured, at the factory, in the mentioned sheet metal container, in such manner that a soldered joint or joints 50 must be separated before the mentioned heating element can be removed, this organization being advantageous as permitting minor repairs, although adapted to prevent tampering by unauthorized persons.

Other objects of our invention will be better understood from the following description of a preferred embodiment thereof, taken in connection with the appended claims and the accompanying drawings, in which

Fig. 1 may be regarded as a plan view, 60 with parts broken away to a substantially median plane.

Fig. 2 is an end view, taken substantially as indicated by the arrow 2 of Fig. 1.

Fig. 3 is a transverse sectional view, taken 65 substantially as indicated by the line 3—3 of Fig. 1.

Fig. 4 is a detail view, taken substantially as indicated by the arrow 4 of Fig. 1.

Fig. 5 is a detail view corresponding to the 70 lower right hand corner of Fig. 1 and illustrating the operation of a thermo-expansive element in the breaking of a circuit.

Fig. 6 is a separate view of a heating element or core of an alternative type herein- 75 after referred to.

Referring to the details of that specific embodiment of our invention chosen for purposes of illustration, 11 may be a sheet metal container, substantially rectangular in outline and preferably comparatively flat and thin, one end 12 of this container being initially left open in order to permit the insertion of a correspondingly shaped but slightly smaller resistance heater 13 therein; and, if 80 desired, the can or container 11 may optionally be provided with a removable cloth cover 14, shown as provided with a puckering string 15 by which it may be secured when, for instance, our heater is to be applied to the 85 human body.

The resistance heater 13 may be formed in various ways, one inexpensive construction comprising, as best shown in Figs. 1 and 3, a plurality of sheets of an inexpensive insulating material, such as asbestos board, a centrally disposed sheet 16 being provided with a resistance element 17, which may be a suitable length of nichrome wire, or the like, wound thereon, the additional sheets 18, 18', 95 whether of the same thickness or of a lesser thickness, being employed primarily as spacing and insulating elements. As shown, the intermediate sheet 16 of asbestos board, or the like, may advantageously be slightly 100 shorter, at one or both ends, than the outer sheets 18, 18'; and filling or spacing elements 19, 19' may optionally be used in conjunction

therewith, at one or both ends of the sheet 16, on which the resistance wire 17, or its equivalent is wound.

An important feature of our present invention is the method or organization by which we may suitably dispose and secure contact elements through which current may be delivered to the wire 17, or its equivalent. For the purpose referred to, we may employ 10 an inner insulating plate 20, to which the respective ends 17^a and 17^b may be secured, as by means of nuts 21 and 21' on screws 22 and 22'; and to the inner insulating plate 20, or its equivalent, we may also secure, as 15 by means of screws 23, 23' stepped spacers 24, 24', adapted to be retained by means such as overlapping straps 25, 25' and 26, 26', which may be soldered together, substantially as shown at 27 in Figs. 2 and 4, in such manner as to prevent access to the screws 23, 23', or unauthorized withdrawal of the described heating element and associated parts.

Instead of connecting the ends of a flexible cord respectively to the screws 22 and 22', or their equivalents, we consider it preferable to use, in conjunction with the mentioned inner insulating plate 20 and the spacers 24, 24', or their equivalents, an outer insulating plate 28 which may be secured by 25 means such as readily accessible screws 29, 29', and which may be provided with a plurality of apertures, such as a pair of smaller openings 30, 30', through which may extend the wires of a flexible cord, and additional apertures 31, 31' adapted to receive 30 screws 32, 32', one or both of which may also serve to retain or engage a contact element extending to or from the binding screw 22 or the binding screw 22'. For example, the 35 screw 32, mentioned as securing one of the wires of a flexible cord, may be adapted directly to engage a resilient clip 33, shown as retained by the head of the binding screw 22; and the screw 32' may serve incidentally 40 to secure a spring contact element 34, having a greater length and normally extending laterally into engagement with the binding screw 22', or into engagement with a contact element retained thereby.

50 When it is considered desirable to provide our electric heater with means for predetermining the maximum temperature thereof, instead of employing a more complicated thermostatic device for this purpose, we may provide circuit breaking means comprising a thermo-expansive element in the form of a mere straight length of suitable wire or rod; and our preferred construction of the element referred to is in fact such that, although its 55 co-efficient of expansion may be important to its suitability, it is immaterial whether or not this element be metallic or non-metallic, conductive or non-conductive. For example, a thermo-expansive rod 35 may be secured at 60 its inner end, or simply inserted in an outer

tubular element or pocket 36, which must have a lesser co-efficient of expansion and which may be threaded or otherwise secured in the insulating plate 20. The rod 35, being slightly longer than the tubular element 36, 70 may normally extend almost into contact with an intermediate portion of the spring contact element 34, so that whenever the said rod is expanded by heat due to the passage of a current through the resistance, electrical current being normally supplied through the screw 22' to the resistance element 17, or its equivalent, as soon as a predetermined temperature is reached, the elongation of the rod 35, or its equivalent, may be effective to 80 lift the end 37 of said resilient contact element from engagement with the screw 22', thereby breaking the circuit and preventing a further rise in temperature, although permitting a reestablishment of the circuit as soon as the temperature drops to the desired level. In order to facilitate precise adjustment of the parts referred to, the resilient contact element 34, or its equivalent, may be provided with adjusting means such as a screw 38, threaded therein and accessible through an additional hole 39 in the outer insulating plate 28.

It being a matter of common observation that great annoyance is occasioned by uncertainty as to whether or not an electrical current is actually passing through electrical heating devices of various sorts, we consider it advantageous to provide our electrical heater with indicating means such as an incandescent bulb 40, shown as secured in an additional and outwardly flared opening 41, and as protected by its interposition between the ends 30, 30' of the flexible cord 42; and a conductive socket 43, into which the bulb 40 is threaded, may be in conductive connection with, for example, the binding screw 32 through the head of which, as described, current may be conducted into the resistance coil 17, or its equivalent; and in order to 100 permit the use of a low-potential bulb in a heater adapted to be interposed in a constant potential system operating at, for example, 110 volts, we may employ means such as a short wire 44, soldered, for example, at a suitable point in the first turn of the resistance wire 17, and connected with a binding screw 45, with which one terminal of the bulb 40 may make contact whenever the said bulb is 115 suitably seated in the socket 43, or its equivalent. Although we may also optionally secure an ordinary switch of any preferred design directly to one of the insulating plates 20 or 28, we consider this unnecessary, it being now possible economically to provide a 120 flexible cord with an interposed switch such as is suggested at 46, in Fig. 1.

The operation of our electric heater will be fully understood from the foregoing description, in connection with which we may 125

add that the heads of the respective screws 29, 29' and the holes in which the screws 32 and 32' are threaded, and optionally also any depressions left above the heads of the screws 5 28, 28', if these be countersunk, may advantageously be filled with a suitable filling, such as cement, to present a uniform appearance and to diminish likelihood of tampering; but we prefer to make the outer insulating plate

10 28 of such length that the same and all parts secured thereto, may be conveniently removed together, rendering all contacts and binding screws easily accessible, whenever the retaining screws 29, 29', which may 15 optionally extend through both the steps 47 of the spacers 24, 24' and the inner insulating plate 20, are withdrawn.

Instead of providing a resistance heater of the specific character illustrated in Figs. 20 1 and 3, we may optionally employ a single insulating core element in the form of, for example, a cast glass plate, the organization illustrated in Fig. 6, for example, comprising a single plate 16', which may be formed 25 of either a fibrous or a non-fibrous insulating material, provided with longitudinal or transverse channels 48 and with notches 49, so disposed relatively thereto that a resistance element 17' may be laced back and forth 30 therethrough, without liability to wear or to an accidental contact of any portion thereof with a metallic container or the like; and this type of heating element may optionally be provided also with a channel or pocket 36' 35 adapted to receive a thermo-expansive element; and when an indicating bulb 40 is to be used in connection therewith a branch for this purpose may be taken off, for example, as suggested at 44' in Fig. 6.

40 Although we have herein described a single complete embodiment of our invention and an alternative type of insulating core for our resistance heating element, it should

be understood that certain features thereof might be independently used and that various modifications may be made by those skilled in the art to which this case relates without the slightest departure from the spirit and scope of our invention, as the same is indicated above and in the following 45 50 claims.

We claim as our invention:

1. An electric heater comprising: a substantially rectangular and flat container open at one end, a heating element comprising an 55 insulating body supporting a resistance extending back and forth relatively thereto; an inner insulating plate carrying inner contacts to which the ends of said resistance are secured; and means near an open end of said 60 container for spacing said inner insulating plate therein, said spacing means being stepped and adapted to interfit with an outer insulating plate carrying outer contacts.

2. An organization as defined in claim 1 in 65 which said inner insulating plate supports a thermo-expansive element disposed between turns of said resistance and adapted to break, at a predetermined temperature, the circuit therethrough; and in which said outer insulating plate carries an adjustable contact element adapted to be moved by said thermo-expansive element. 70

3. An organization as defined in claim 1 in 75 which said spacing means are adapted to support an outer insulating plate, and in which said outer insulating plate is provided with a resilient contact element carrying an externally accessible adjusting screw engageable by a thermo-expansive element. 80

In testimony whereof, we have hereunto set our hands at Los Angeles, California, this 27th day of January, 1925.

EDWIN R. CROOKER.
